UNITED STATES PATENT OFFICE.

WILLIAM S. TRASK, OF NEW BRITAIN, CONNECTICUT, ASSIGNOR TO P. & F. CORBIN, OF NEW BRITAIN, CONNECTICUT, A CORPORATION OF CONNECTICUT.

COMPENSATOR FOR KNOB-SPINDLES.

No. 923,091.

Specification of Letters Patent.

Patented May 25, 1909.

Application filed August 21, 1908. Serial No. 449,665.

To all whom it may concern:

Be it known that I, WILLIAM S. TRASK, a citizen of the United States, residing at New Britain, county of Hartford, State of Connecticut, have invented certain new and useful Improvements in Compensators for Knob-Spindles, of which the following is a full, clear, and exact description.

My invention relates to improvements in means for mounting a knob and knob spindle upon a door. In the usual method of so mounting the spindle and knobs upon the door, it is common practice when the spindle is of such length with respect to the thickness 10 of the door that there would be end movement of the knobs, to take up this movement by placing one or more washers upon the spindle adjacent each knob. This not only results in unsightly construction, but frequently it is impossible to entirely obviate such end play, and on the other hand when the washers are so arranged as to take up the end play, undue friction frequently results between the knobs and such washers.

25 The object of the invention is to prevent end play of the knobs irrespective of the thickness of the door to which they are applied.

A further object of the invention is to provide means whereby the knob spindle will be supported at several points in addition to the support afforded by the lock through which the spindle passes, whereby the spindle and knobs will be held against rocking movement.

35 A further object is to reduce to a minimum the friction between the knobs and spindle, and their supporting parts.

A preferred embodiment of my invention 40 is illustrated in the accompanying drawings, in which,

Figure 1 is a view partly in section of a knob and its spindle, and the improved support therefor of my invention. Fig. 2 is a 45 plan view of the assembled knob support. Fig. 3 comprises an edge and interior view of one of the members of the knob support. Fig. 4 comprises similar views of a coöperating member. Fig. 5 shows a bail for holding 50 the parts in assembled position. Fig. 6 shows a spring which is interposed between the parts in Figs. 3 and 4. Fig. 7 shows a modified view of the invention, and, Fig. 8 illustrates a detail of such modification.

55 In the embodiment of my invention illus-

trated in Fig. 1, 1 is a door knob and 2 is the spindle to which it is suitably secured.

3 shows the usual escutcheon plate which is suitably secured to the stile 4 of the door, through which and through a drilled hole 5 in said stile, the knob spindle passes, the lock mechanism (not shown) being secured within the mortise in the stile, one wall of which mortise is shown at 6. The escutcheon 3 may be provided with the usual thimble 7 secured thereto in any desired manner.

In the ordinary method of mounting the knobs and spindle upon the door, side play or rocking of the spindle and knobs is prevented to more or less extent by the contact 70 of the shank of the knob with the thimble 7, and end play of the knob and spindle is taken up or provided for by means of washers on the spindle interposed between the knob shank and the outer surface of the stile. In

75 my improved construction, and in the embodiment illustrated in Fig. 1, the stile is countersunk at 8 and a thimble 9 having a flange 10 is placed in said countersunk portion to form a socket or recess to receive the 80 compensator and bearing of my invention.

This compensator comprises two telescoping cup-shaped members or thimbles 11 and 12, the member 12 being seated entirely within the countersunk thimble 9 and the member 85 11 projecting through the thimble receiving apertures of the escutcheon 3, and having a lateral bearing upon and within the perimeter of the thimble 7. A spring 13 is interposed between the compensator members 11

90 and 12 and said members are held together by means of a bail 14, the extremities 15 of which are inturned and take within aperture 16 in the wall of the compensator member 12 and within slots 17 in the wall of the compensator member 11. The slots 17 in the member 11 provide for telescopic or collapsing movement of said member within the co-operating member 12 of the compensator.

95 The members 11 and 12 are provided with 100 spindle receiving apertures 18 and 19 respectively, which are preferably of the same shape and of substantially the same area as the cross section of said spindle, but it is within the scope of my invention to make 105

these apertures of a different shape and if desired of a larger cross-sectional area than the cross sectional area of the spindle so long as they are so shaped as to center the said spindle.

By the above described construction, the spring-actuated members 11 and 12 automatically compensate for any disparity between the thickness of the door and the distance between the knobs on the knob spindle whereby end play between the door and the knobs is constantly taken up and the knobs are securely held in proper position and adjustment with respect to the door.

10 Furthermore, when the apertures 18 and 19 and the compensator members 11 and 12 are of such shape or area as to contact with the spindle, it will be seen that the compensator forms a bearing for the spindle and knobs 15 against lateral rocking movement by reason of the bearing of the member 11 of the compensator upon the aperture in the escutcheon or upon the thimble 7 within said aperture. By this construction bearing points are provided outside of and considerably removed 20 from that of the lock mechanism through which the spindle passes, and the spindle and knobs will be at all times securely held in proper alignment in the stile of the door.

25 Furthermore, when the apertures in the compensator members 11 and 12 are such that the same are held against rotation upon the spindle, the compensator will rotate with the spindle and knobs, thus doing away with 30 friction between the knob shank and the outer surface of the member 11 of the compensating means. Hence, while the knobs are securely held against end thrusts, the means for this purpose will not produce 35 undue friction against the rotation of the knobs. In some constructions however, it may be desirable that the compensator act only as a compensator against end thrusts and not necessarily to afford extra bearings for the 40 knob spindle and knobs. In such case, the apertures 18 and 19 in the members 11 and 12 of the compensator may be of larger area than the cross section of the spindle, whereby the spindle will turn within the compensator.

45 In the modified form illustrated in Fig. 7 is shown a method of mounting the compensator in what is known as a hollow or dished escutcheon. The escutcheon 20 here shown is flanged at 21, whereby there is a space 22 50 between the escutcheon and the stile 4 of the door, and the compensator receiving thimble 23 corresponding to the thimble 9 of the construction above described is secured to the rear side of the escutcheon as by an over-turned lip 24 of the thimble 25. The member 12 of the compensator is here seated against a washer 26, which in turn is supported by inturned lugs or tongues 27 struck up from the thimble 23. The member 11 of 55 the compensator projects as above described through the aperture in the escutcheon 20 and as here shown has a bearing within the lip 24 of the thimble 25. The operation of the compensator in this modification may be 60 65 and is the same as that described for the

form illustrated in Fig. 1. In this modified form furthermore, the compensator receiving thimble 23 may be of such a depth as to be flush with the inner edge of the flange 21 whereby said thimble also performs the function of a support for the escutcheon against the end thrusts of the knob and against any other pressure which may be brought to bear upon the escutcheon.

While I have here shown and described a particular construction and arrangement of compensating means, it is to be understood that the same may be altered in detail without departing from the spirit and scope of my invention.

Another distinct advantage of combining in this particular connection the spring compensator device is that it performs the second function of forcing the knob 1 longitudinally upon the spindle 2 in such a manner as to set up a friction between the knob retaining screw and the spindle 2, thus preventing said screw from working loose and falling out. In the drawing, the usual knob retaining screw is indicated at 1^a the same 90 passing through a hole in the knob shank and taking out a threaded screw passage in the spindle in the usual well known manner. In common practice these knob spindles are provided with a series of screw passages to 95 enable the knob to be applied to doors of different thicknesses, that particular screw passage most conveniently located with reference to the screw passage in the knob shank being the one selected.

100 What I claim is:

1. In a spindle support and knob compensating device, an escutcheon, a compensator rotatably mounted in said escutcheon and having a passage therethrough to receive a knob spindle, said compensator comprising two yielding parts, and means for normally expanding the same, one of said parts having a passage therethrough arranged to permit a knob spindle to pass 105 through said compensator but preventing the independent rotation of said spindle therein.

2. In a device of the character described, a knob spindle, a knob carried thereby and a 110 compensator for taking up the end play of said knob and spindle, said compensator comprising two telescopic members and a spring interposed between said members.

3. In a device of the character described, a 115 knob spindle, a knob carried thereby and a compensator for taking up the end play of said knob and spindle, said compensator comprising connected telescoping members and a spring interposed between said members.

4. In a device of the character described, a 120 knob spindle, a knob carried thereby and a compensator for taking up the end play of said knob and spindle, said compensator 125 comprising

comprising two companion telescopic members and means to hold said members in assembled position while permitting collapsible movement thereof.

5. In a device of the character described, a knob spindle, a knob carried thereby, a flanged or hollow escutcheon plate, a compensator case and means therein for taking the end thrust of said spindle said case being mounted at the rear of said escutcheon plate and forming a support for said spindle.
10. In a device of the character described, a

knob spindle, a knob carried thereby, a flanged or hollow escutcheon plate, a compensator case and means therein for taking the end thrust of said spindle said case being mounted upon said escutcheon plate at its rear and having a rotatable bearing therein, said compensator also operating to take the side strain of said spindle.
